UNITED STATES PATENT OFFICE

149,934

DESIGN FOR A PLIER WRENCH

Jay T. Cobb, Altus, Okla.

Application March 19, 1946, Serial No. 127,650

Term of patent 14 years

(Cl. D54—13)

To all whom it may concern:

Be it known that I, Jay T. Cobb, a citizen of the United States of America, residing at Altus, in the county of Jackson and State of Oklahoma, have invented a new, original, and ornamental Design for a Plier Wrench, of which the following is a specification, reference being had to the accompanying drawing, forming part thereof.

Figure 1 is a perspective view of a plier wrench showing my new design.

Figure 2 is a perspective view showing the opposite side of the plier wrench.

I claim:

The ornamental design for a plier wrench, as shown.

JAY T. COBB.
